SPINNING AND TWISTING MACHINE

Harold Arthur Boyd, Glasgow, Scotland

Application March 28, 1945, Serial No. 535,285
In Great Britain April 20, 1944

5 Claims. (Cl. 57—104)

1

This invention relates to improvements in driving arrangements for spindles or flyers in ordinary spinning or twisting machines and also stop motion machines, which may be of the type described in the specification of British Patent No. 113,687.

In present-day practice a spindle or group of spindles or flyers is driven by a single tape or cord from a main driving drum which runs the length of the frame. This tape or cord in most cases requires to be light and flexible as it has to pass around a small diameter whorl on the driven spindle or flyer. The said tape or cord may be tensioned by an auxiliary weighted movable tension pulley, around which the tape or cord runs and whereby it is kept tight.

According to the present invention we interpolate in the drive between the main driving drum and the spinning spindles or flyers intermediate whorls each adapted to move laterally towards or away from the respective spinning spindle or flyer, adapted to be driven by a primary tape or cord driven from the main drum and maintained under tension, and also adapted to drive a secondary tape or cord passing around a whorl on the spindle or flyer, lateral movement of said intermediate whorl serving to tension the secondary tape of cord.

As the intermediate whorl may be larger than the whorl mounted on the associated spinning spindle or flyer, it can carry a much heavier primary driving tape or cord, giving longer life and a positive drive, while the secondary tape or cord may be made endless as it does not pass around the main driving drum. The endless tape or cord may be slipped on to the respective whorls (not sewn in place on the spinning frame) and has a longer life than tapes or cords of other types.

When an intermediate whorl, mounted as described, is used on a stop motion machine, it is also adapted to be moved towards the spinning spindle or flyer by hand or automatically, and thus to slacken the secondary tape or cord which then ceases to move, so that the spindle or flyer stops while the primary tape or cord continues to run as usual.

In addition to the lateral movement the intermediate whorl may be given an axial movement, to bring a dead surface which is coaxial with the said intermediate whorl into the plane of the secondary tape or cord and of the associated whorl on the driven spindle or flyer, so that a quicker stop is brought about.

In what follows we shall assume that one pri-

2

mary tape or cord serves a plurality of spindles or flyers.

In the accompanying drawings Fig. 1 is an elevation partly in section and Fig. 2 a diagrammatic plan illustrating a spindle drive according to the invention as applied to a double-sided machine. Fig. 3 is a diagrammatic elevation showing a modification as applied to a single-sided machine.

10 The practical application of the invention illustrated in Figs. 1 and 2 is adapted to a machine with ordinary framework as shown in British patent specification No. 113,687, with twisting spindles 3, a main driving drum 1, and 15 a swinging weighted tension pulley 4. Behind the spindles 3 and between them and the drum 1 we mount rods 20 substantially parallel to the respective spindles 3, one rod for each spindle. On these rods we pivot brackets 21 for swinging 20 movement. To one side of each rod 20 we mount on the respective swinging bracket 21 a dead spindle 22. On each dead spindle 22 we mount an intermediate whorl 23 of sufficient axial length to carry two tapes one above the other. The 25 primary driving tape 2 comes from the main drum 1 and passes round the tension pulley 4 and around the driven portion of each of two intermediate whorls 23 on each side of the frame (four in all), and back to the drum 1. On the 30 lower or driving part of each intermediate whorl 23 we mount a secondary tape 2^a, the said tape passing around the whorl 23 of one twisting spindle 3. In line with the intermediate whorl 23 we mount on the dead spindle 22 a collar 24 of 35 approximately the same diameter as the whorl 23. Above the intermediate whorl 23 we mount a lever 25 on a horizontal stud 26. At one end of one arm of the lever 25 is a weight; the other arm of the lever 25 is connected to a preferably 40 upright rod 6 with a catch 6' normally preventing it from moving upwards, said rod 6 being in operative connection with thread feeler mechanism of the kind described in the said specification No. 113,687. The second arm of 45 the lever 25 is also connected by a wire link 27 to the swinging bracket 21 by engagement with an eye 22^a in the end of the dead spindle 22. On being disengaged from its catch 6' by operation of the thread feeler mechanism due to failure 50 of thread, the upright rod 6 moves upwards on the tilting of the lever 25. A depending arm 28 on the lever 25 abuts against the back of the swinging bracket 21 and forces it towards the spindle 3 and thereby slackens the secondary 55 tape 2^a. As the end of the second arm of the

lever 25 rises, it also shifts, through the link 27, the swinging bracket 21, the whorl 23 and the dead collar 24 in axial direction. The slackened secondary tape 2^a then rests on the dead surface 24 and stops, while the primary tape 2 continues to run. When the upright rod 6 is again depressed into its catch 6', the operations are reversed—the tape 2^a slips back on to its driver and is tightened, and so drives the spindle 3.

The lever 25 with connections may be dispensed with when stopping of individual spindles is not required.

The intermediate whorls 23 are shown as being rotatable about vertical axes; they may, however, be rotatable about horizontal or inclined axes.

In the modification illustrated in Fig. 3 the intermediate whorl 23 is devised to apply tension to the tapes 2, 2^a in two directions approximately at right angles to one another, namely, to the primary tape 2 which is approximately vertical and which drives the intermediate whorl 23 from the main driving drum 1, and to the secondary tape 2^a which runs substantially horizontally from the intermediate whorl 23 to the flyer or spindle whorl 3^a.

The intermediate whorl 23 is mounted above the drum 1 on the inner arm of a horizontal two-armed lever 30 which is mounted on a fulcrum stud 31 and to the outer arm of which lever is applied a weight whereby to exercise an upward effort on the whorl 23 and thus to apply tension in vertical direction to the primary tape 2.

The fulcrum stud 31 is carried by an upstanding arm 32 of a bell-crank lever 32, 33 which is mounted on a shaft or stud 34 the axis of which is parallel to the axes of the whorl 23 and of the drum 1, the other arm of said bell-crank lever

extending substantially horizontally in the direction away from the flyer or spindle and being influenced by a weight whereby to urge the whorl 23 horizontally in the direction away from the flyer or spindle whorl and thus apply tension in a horizontal direction to the secondary tape 2^a.

What is claimed is:

1. In a spinning or twisting machine, the combination with a main driving drum and a spindle having a whorl, of an intermediate whorl movable laterally towards and away from said spindle, a primary flexible driving element connecting said main driving drum and said intermediate whorl, and a secondary flexible driving element connecting said intermediate whorl and said spindle whorl.

2. In a spinning or twisting machine, the combination claimed in claim 1 in which the intermediate whorl is carried on a movable bracket and adapted, when it is desired to stop the spindle, to be moved towards the spindle, to slacken the secondary flexible driving element.

3. In a spinning or twisting machine, the combination claimed in claim 1 including a dead surface coaxial with the intermediate whorl, said intermediate whorl and dead surface being adapted to move axially to bring the dead surface into the plane of the spindle whorl.

4. In a spinning or twisting machine, the combination claimed in claim 1 in which a single tension pulley applies tension to both the primary and the secondary flexible driving elements.

5. In a spinning or twisting machine, the combination claimed in claim 1 in which the intermediate whorl is arranged to apply tension to the flexible driving elements in two directions at right angles to one another.

HAROLD ARTHUR BOYD.
